Primary Examiner — Selina Sikder

(74) *Attorney, Agent, or Firm* — Law Offices of Lisa & Lesko, LLC; Justin Lesko, Esq.

(57) **CLAIM**

I claim the ornamental design for a mud ring, substantially as shown and described.

DESCRIPTION

FIG. 1 is a front perspective view of the mud ring.

FIG. 2 is a top view of FIG. 1.

FIG. 3 is a bottom view of FIG. 1.

FIG. 4 is a left side view of FIG. 1.

FIG. 5 is a right side view of FIG. 1.

FIG. 6 is a front view of FIG. 1.

FIG. 7 is a back view of FIG. 1.

FIG. 8 is a front perspective view of a second embodiment of the mud ring.

FIG. 9 is a top view of FIG. 8.

FIG. 10 is a bottom view of FIG. 8.

FIG. 11 is a left side view of FIG. 8.

FIG. 12 is a right side view of FIG. 8.

FIG. 13 is a front view of FIG. 8.

FIG. 14 is a back view of FIG. 8.

FIG. 15 is a front perspective view of a third embodiment of the mud ring.

FIG. 16 is a top view of FIG. 15.

FIG. 17 is a bottom view of FIG. 15.

FIG. 18 is a left side view of FIG. 15.

FIG. 19 is a right side view of FIG. 15.

FIG. 20 is a front view of FIG. 15.

FIG. 21 is a back view of FIG. 15.

FIG. 22 is a front perspective view of a fourth embodiment of the mud ring.

FIG. 23 is a top view of FIG. 22.

FIG. 24 is a bottom view of FIG. 22.

FIG. 25 is a left view of FIG. 22.

FIG. 26 is a right view of FIG. 22.

FIG. 27 is a front view of FIG. 22; and,

FIG. 28 is a back view of FIG. 22.
